(57) CLAIM

The ornamental design for a golf club head cover, as shown and described.

DESCRIPTION

FIG. 1 is a perspective view of our new golf club head cover design;

FIG. 2 is a top view thereof;

FIG. 3 is a right side view thereof;

FIG. 4 is a front view thereof; and,

FIG. 5 is a left side view thereof.

The part of a golf club head cover shown in phantom does not form any portion of the present invention.

1 Claim, 2 Drawing Sheets
